UNITED STATES PATENT OFFICE

2,488,099

CONTROL APPARATUS

Alexander W. Plensler, Chicago, Ill., assignor to
 Belmont Radio Corporation, Chicago, Ill., a corporation of Illinois

Application March 2, 1946, Serial No. 651,636

13 Claims. (Cl. 74—10.35)

1

The present invention relates to control apparatus for radio receivers and more particularly to manually operable automatic tuners of the mechanical type for such receivers. Specifically the present invention is concerned with an improvement on Plensler Patent No. 2,272,922 granted February 10, 1942, and assigned to the same assignee as the present application.

Many types of modern radio receivers are provided with automatic tuning mechanisms. In general such automatic tuners comprise a series of manually actuated push buttons which enable the listener to selectively tune in particular stations merely by pushing or actuating the push buttons. In addition the receiver includes manual means for tuning the receiver to any other broadcasting station within the range of the receiver, in addition to those for which the automatic tuning arrangement including the push buttons is set. In one form of automatic tuner for radio receivers a series of variably positioned cams are provided along the tuning shaft, one for each of the push buttons. Suitable cam locking means are provided for holding these cams in their predetermined positions relative to the tuning shaft so that when a push button is actuated, the associated cam is rotated with the consequent rotation of the tuning shaft to a predetermined position corresponding to the particular station setting for which the push button and associated cam have been adjusted. In order initially to set the automatic tuning arrangement or to change the setting thereof, it is necessary to operate some means for locking a particular cam to the tuning shaft so that relative movement between this cam and the tuning shaft can be obtained. The present invention is particularly concerned with a new and improved arrangement for locking the cams to the tuning shaft which locking means may be operated in a simple manner without additional equipment to afford a new setting or adjustment, and so constructed that the unlocking of any particular cam does not unlock the other cams.

It is an object of the present invention to provide a new and improved automatic tuning mechanism which is simple and inexpensive to manufacture, foolproof in operation and satisfactory in every respect from the standpoint of the radio listener who operates the receiver.

A further object of the present invention is to provide a new and improved automatic tuner which can be set and reset merely by manipulation of the tuning mechanism itself without the requirement of extra tools or equipment.

2

A still further object of the present invention is to provide a new and improved manually operated automatic tuner for radio receivers having a plurality of control elements on a rotary shaft, with each control element adapted to be set or reset to a predetermined position independently of the other control elements, and while maintaining such other control elements in a fixed position on the rotary shaft.

Still another object of the present invention is to provide a new and improved cam locking means for an automatic tuner for a radio receiver which comprises friction means for engaging a large area of the tuning shaft.

Further objects and advantages of the present invention will become apparent as the following description proceeds and the features of novelty which characterize the present invention will be pointed out with particularity in the claims annexed to and forming a part of this specification.

For a better understanding of the present invention reference may be had to the accompanying drawings in which:

Fig. 1 is a fragmentary plan view of the tuner structure of a radio receiver embodying the present invention;

Fig. 2 is a sectional view taken along line 2—2 of Fig. 1 but showing the push button in its depressed position for tuning in a particular station, but not sufficiently depressed for unlocking the cam;

Fig. 3 is a side elevational view of one of the tuning elements of Fig. 1 taken along line 3—3 of Fig. 2;

Fig. 4 is an exploded perspective view of the tuning mechanism of the present invention;

Fig. 5 is a sectional view taken on line 5—5 of Fig. 1;

Fig. 6 is a sectional view taken on line 6—6 of Fig. 5, assuming that Fig. 5 shows a complete structure; and

Fig. 7 is also a sectional view taken on line 7—7 of Fig. 5, again assuming that Fig. 5 shows a complete structure.

Although the present invention is applicable to various forms of automatic tuners for radio receivers it has been illustrated specifically in the drawings as applied to an automatic tuner of the type disclosed and claimed in the above-mentioned Plensler patent.

Referring now to the drawings there is illustrated a tuning mechanism for a radio receiver which comprises a rotary shaft 10 which is suitably journaled in a frame, a portion of which is shown at 11. The rotary shaft 10 is coupled or

otherwise connected to a suitable resonance frequency changing means for tuning the radio receiver to particular stations. In Fig. 1 this resonant frequency changing means is illustrated as a variable condenser 12 having a rotor portion rotatable through an angle of substantially 180°, but it should be understood that it might also comprise a variable inductance or the like. Rotation of shaft 10 will cause the capacitance of variable condenser 12 to vary with the resultant tuning of the radio set to any desired station within the range of the receiver. To accomplish this a suitable tuning knob, not shown, may be provided in a manner well understood by those skilled in the art.

In accordance with the now well-known automatic mechanical tuning mechanisms for radio receivers, shaft 10 is also controllable by a plurality of push buttons or the like whereby particular stations to which the listener frequently desires to listen may be tuned in merely by actuating one of the push buttons which automatically causes the desired rotation to be imparted to shaft 10 without further effort than to actuate one of the push buttons.

It should be understood that each push button may be associated with a selector unit comprising a slidable member which is moved in a generally longitudinal direction upon actuating the push button as is shown in the above-mentioned Plensler patent, or each push button may be associated with a selector unit comprising members rotatably or pivotally mounted on a suitable support. The present invention is illustrated in connection with the latter type of selector unit. As illustrated in the drawings and particularly in Fig. 1, two separate selector units generally indicated as 13a and 13b have been illustrated, each being provided with a manually actuatable push button portion 14. Actually additional selector units and associated push buttons could be provided, the number depending upon the number of stations to which the receiver is to be tuned merely by actuating a particular push button. A radio receiver might have as few as 3 or 4 push buttons or 10 or 12 or more. The sole purpose of each individual selector unit is to impart a predetermined rotation to shaft 10, which rotation is different for each selector unit. Since each of the selector units are identical in every respect only one, namely 13a, will be described hereinafter.

Selector units such as 13a and 13b described in greater detail hereinafter are each adapted to engage and actuate a cooperating heart-shaped cam 15 to impart different desired station settings to tuning shaft 10. Normally each cam 15 is locked or retained against rotation or movement relative to tuning shaft 10 and the present invention is particularly concerned with new and improved locking or clamping means together with simple means for locking and unlocking the same, the unlocking mechanism operating only on the particular cam being reset.

The selector unit 13a which is identical with all the other selector units which may be included in the particular radio receiver comprises a finger actuated lever assembly by means of which the desired setting of cam 15 and, consequently, tuning shaft 10 may readily be obtained. This lever assembly comprises a first or actuating lever 16 and a second or actuated lever 17. Lever 17 is provided with an angularly positioned notch 18 so that it may be slipped over and pivotally mounted on a suitable supporting shaft 19

which is fixedly supported by the frame 11 and which preferably extends along the tuning shaft 10 in parallel relationship therewith. Actuated lever 17 is provided at one end thereof with a roller 20 rotatable on a suitable offset portion 11a of lever 17. Roller 20 is adapted to engage the periphery of heart-shaped cam 15 to effect rotation of cam 15 and, consequently, tuning shaft 10 to the position indicated in Fig. 2 where the roller 20 is positioned in the low point of the cam periphery. Lever 17 is preferably pivotally mounted intermediate the ends thereof so that the end of lever 17 not provided with roller 20 extends in a direction toward the associated push button 14.

Shaft 19 also pivotally supports the actuating lever 16 which is provided with a notched-out portion 21 for engaging shaft 19. Preferably shaft 19 is provided with reduced diameter portions at the pivot points of levers 16 and 17 for proper positioning thereof or suitable spacers may be provided on shaft 19 between levers 16 and 17 which would have the same effect. As illustrated, push button 14 is integrally formed with the lever 16 and is illustrated as a laterally projecting portion thereof. As best shown in Figs. 2 and 4 the lever 16 actually has two integral legs or arms arranged at a substantial angle with respect to each other; a leg 16a from which push button 14 extends in a lateral direction and a leg 16b which is provided with a pair of resetting prongs 22 and 23. The resetting prong 23, as is best shown in Fig. 4, is offset with respect to the main body portion of lever 16, and, consequently, also with resetting prong 22. With this arrangement one resetting prong is positioned in a plane parallel to but on one side of cam 15 while the other resetting prong is positioned in a plane parallel to but on the other side of cam 15.

With the arrangement described thus far it is obvious that some means must be provided to impart the force applied to push button 14 and lever 16 to actuated-lever 17, and, consequently, to cam 15. As illustrated in the drawings the actuating force is transmitted from lever 16 to lever 17 through a coiled compression spring 24 having its ends telescoped over integral projection portions 16c and 17b positioned near the inner ends of the two levers 16 and 17, respectively. Relative movement between the levers 16 and 17 under the influence of spring 24 is limited by a stop portion 16d projecting laterally from the arm 16a of lever 16 in the path of movement of the end of lever 17 which does not support the roller 20. Preferably stop 16d is integrally formed with lever 16 in the same manner as push button 14.

Assuming for the moment that cam 15 is rigidly locked to tuning shaft 10 and that it is in a position other than that shown in Fig. 2, depression of push button 14 will cause clockwise rotation of lever 16 as viewed in Fig. 2 and a compression of spring 24 with consequent movement of lever 17 also in a clockwise direction about shaft 19, with the resultant engagement of roller 20 with the periphery of cam 15 so that cam 15 is rotated to the position shown in Fig. 2.

In order that the relative position of cam 15 with respect to tuning shaft 10 may be varied so that each push button may control a desired station through its associated cam it is necessary to provide means for adjusting cam 15 relative to shaft 10. One scheme for accomplishing this would be to fasten cam 15 to shaft 10 by means of

a set screw. This would require the use of a screw driver or wrench or some other tool which is unsatisfactory or the means disclosed in the above cited Plensler patent and the present invention is concerned with a locking or frictional engaging means for locking cam 15 to shaft 10, which means may be released in a simple manner for adjusting the relative positions of cam 15 and shaft 10 and yet which provides a very large area of frictional engagement, without the intervention of any tools.

In accordance with the present invention this locking means essentially comprises a pair of spirally wound springs 25 and 26 illustrated as formed of flat material, as is clearly shown in Figs. 4 and 5. These springs are preferably combined into a single continuous spring but are here discussed as a pair for purposes of simplifying the explanation. Springs 25 and 26 are each coaxially positioned relative to shaft 10, one on either side of cam 15, thereby enveloping a portion of shaft 10. Preferably springs 25 and 26 are housed in suitable cuplike members or hubs 27 and 28, respectively, one positioned on either side of cam 15 and spaced from one another by cam 15. Spiral springs 25 and 26 are each spiraled in the same direction when properly positioned on tuning shaft 10. The ends of springs 25 and 26 adjacent cam 15 are fixedly secured to cam 15 by brazing or the like, as is indicated at 29 best shown in Figs. 5 and 6. The other ends of the springs 25 and 26 remote from cam 15 are fixedly secured to their associated hubs 27 and 28, respectively, as is clearly shown at 29' in Figs. 5 and 7. With this construction it will be noted that by rotating hubs 27 and 28 in opposite directions about the shaft 10, springs 25 and 26 may either be wound tightly against shaft 10 to prevent relative movement between shaft 10 and cam 15 or may, upon reverse rotation of hubs 27 and 28 relative to each other, be unwound to release the gripping force exerted by their turns or convolutions upon shaft 10 and thus permit relative rotation between shaft 10 and cam 15. In the particular instrumentation as illustrated in Figs. 2 and 4, clockwise rotation of hub 28 performs the locking operation.

It is desired that the cam 15 is normally locked or fixed with respect to tuning shaft 10 to prevent relative rotation between shaft 10 and cam 15. In connection with the present invention, therefore, it is desirable that means be provided which normally cause hubs 27 and 28 to be rotated in opposite directions about the shaft 10 so as to cause the turns or convolutions of springs 25 and 26 to grip tightly shaft 10, thereby preventing relative movement between shaft 10 and cam 15. To accomplish this there are provided ring members 30 and 31, respectively, associated with hubs 27 and 28. The ring member 30 comprises a ring portion which is adapted to be slipped over the hub 27 so as to be brazed or otherwise suitably fastened as indicated at 32, to an enlarged portion 27a of hub 27. Similarly the ring member 31 is arranged to be suitably fastened as indicated at 32 to an enlarged portion 28a of hub 28. Integrally connected to ring member 30 is an arm 30a provided with a slot 30b which arm 30a extends in a direction parallel with the plane of cam 15. Also integrally connected with ring member 30 in substantially diametrically opposed relationship to arm 30b is a second arm 30c which is provided with a laterally projecting portion 30d adapted to extend through an enlarged opening 33 in cam 15 so that the end thereof is on the op-

posite side of cam 15 from ring member 30. The portion 30d is adapted to be positioned in the path of resetting prong 23 as will become apparent from the following description. Ring member 31 on the other hand also is provided with an arm 31a corresponding to arm 30a of ring member 30, which arm 31a is provided with a notched-out portion 31b. A second arm 31c integrally formed with ring member 31 and positioned in substantially diametrically opposed relationship with respect to arm 31a includes a laterally projecting portion 31d which is positioned so as to extend through an opening 34 in cam 15 which is very similar to the opening 33 mentioned above, but spaced therefrom in a manner clearly shown in Figs. 2 and 4. The laterally projecting portion 31d of ring member 31 extends into the path of movement of resetting prong 22.

In order to bias hubs 27 and 28 to rotate in opposite directions to cause springs 25 and 26 to frictionally engage or clamp tuning shaft 10, arms 30a and 31a of ring members 30 and 31 which extend on opposite sides of cam 15, are interconnected by a tension spring 35, the ends of which are hooked in notched-out portions 30b and 31b, respectively. An elongated opening 36 in cam 15 is provided to permit spring 35 to interconnect arms 30a and 31a which are on opposite sides of cam 15. As is obvious from Figs. 1 and 3, spring 35 extends from one side of cam 15 to the other through opening 36.

With the arrangement described, spring 35 tends to cause rotation of hubs 27 and 28 in opposite directions about the shaft 10, hub 28 rotating in a clockwise direction as viewed in Figs. 2 and 4 so that the turns or convolutions of springs 25 and 26 are caused tightly to grip shaft 10, thereby frictionally locking cam 15 to shaft 10. Relative movement between cam 15 and shaft 10 can be obtained by removing the friction provided by the convolutions of springs 25 and 26 gripping shaft 10, as will be hereinafter described.

During a normal operation of the selector unit including the lever assembly comprising levers 16 and 17, by depressing push button 14 the cam 15 is rotated to a predetermined position without resetting prongs 22 and 23 engaging with or moving the arms 30d and 31d of ring members 30 and 31, respectively. When, however, it is desired to set or reset the cam 15 relative to shaft 10 to change the station setting or to initially establish a station setting, push button 14 is depressed to a greater extent than would normally be required for tuning the station whereby resetting prongs 22 and 23 engaging with arms 30d and 31d of ring members 30 and 31, respectively, cause rotation of hubs 27 and 28 in opposite directions to effect unwinding of springs 25 and 26, thereby relieving the clamping force exerted by these springs upon shaft 10. Shaft 10 can now be rotated to a new station setting while cam 15 is held stationary by the pressure of roller 20. After the new shaft setting of shaft 10 is established by manually rotating shaft 10 through conventional tuning means, not shown, the lever 16 may be released, whereupon spring 35 will draw arms 30a and 31a towards each other to cause springs 25 and 26 again tightly to grip shaft 10, thereby relocking cam 15 to shaft 10 in this new position.

In order to prevent a possible inadvertent unlocking of the cam 15 relative to the shaft 10, there may be provided an interference member 37 in the form of a rod eccentrically mounted as indicated at 38 in frame member 11 and extending for the full length of the tuning shaft 10. When

the rod 37 is in the position shown in Fig. 2 the upper surface thereof acts as a stop for arm 16a of lever 16 so that pivotal movement of lever 16 beyond that required for movement of cam 15 to the proper position without unlocking cam 15 relative to shaft 10 is prevented. When stop 37 is rotated about eccentric axis 38, further pivotal movement of lever 16 is permitted whereby unlocking of cam 15 with respect to shaft 10 in the manner described above can be obtained.

The operation of the selector unit 13a to rotate a corresponding control element such as cam 15 and thereby to rotate tuning shaft 10 to a predetermined tuning position for the condenser 12 is apparent from the description above. In setting a cam 15 to an original predetermined position or resetting it to a subsequent predetermined position, the eccentric 37, if such an element has been provided, is moved from the position shown in Fig. 2 so as not to interfere with further downward movement of lever 16. When the eccentric 37 is thus moved out of its interfering position, push button 14 is actuated to cause further clockwise rotation of lever 16 about the shaft 19 whereby resetting prong 22 engages member 31d and resetting prong 23 engages member 30d. Further movement of lever 16 about the shaft 19 causes ring members 30 and 31 to be rotated in opposite directions against the force of tension spring 35. Since ring members 30 and 31 are fastened to hubs 27 and 28, respectively, rotation of hubs 27 and 28 results. Furthermore, since the ends of spiral springs 25 and 26 are suitably fastened to hubs 27 and 28, spiral springs 25 and 26 are unwound so as no longer to frictionally grip shaft 10 and shaft 10 is therefore free to move or rotate relative to cam 15 which is held stationary by the selector unit. Accordingly, tuning shaft 10 and the associated condenser 12 are moved to a position corresponding to the desired tuning position which will be indicated by a suitable dial on the radio receiver not shown. When this predetermined tuning position has been obtained push button 14 is released and spring 35, acting through ring members 30 and 31 causes rotation of spiral springs 25 and 26 in opposite directions so as to be wound tightly on shaft 10 frictionally engaging the same whereby cam 15 is locked to shaft 10. Spring 24 causes lever 16 to return to its initial position when pressure is released from push button 14. The interference member 37 should be returned to the position shown in Fig. 2 following such an adjusting operation.

From the above description it is apparent that the present invention provides a simplified, sturdy, manually operable tuner for a radio receiver in which the tuning operations for initially setting or resetting the cam relative to the tuning shaft can be accomplished merely by actuating the push button device itself. Furthermore, a very positive arrangement for locking the cam or a plurality of them to the tuning shaft is provided, which locking arrangement of any desired cam is released in a simple manner. The area of frictional engagement of the locking means of the present invention is very large since a large number of turns may be provided for springs 25 and 26 without taking up any additional space in the radio receiver, thus providing full assurance that once the locking function is performed relative movement between cam 15 and tuning shaft 10 cannot occur. In addition to the above advantages the present invention provides for a very foolproof construc-

tion which is simple to assemble and inexpensive to manufacture.

It will be apparent to those skilled in the art that the present invention is not limited to the particular construction shown, but various changes and modifications may be made without departing from the spirit and scope thereof, and it is aimed in the appended claims to cover all such changes and modifications as fall within the true spirit and scope of the present invention.

I claim:

1. A control device for a radio receiver including a rotary tuning shaft, a cam mounted on said shaft for relative movement therewith, a pair of spirally wound spring means coaxially arranged with respect to said shaft and positioned one on either side of said cam with the ends adjacent to said cam fastened thereto, means for applying opposed rotary forces to the ends of said spring means not fastened to said cam to cause the turns of said spring means to grip said shaft and fixedly hold said shaft and cam as a unit, a selector unit for causing rotation of said cam and tuning shaft as a unit, and means on said selector unit for applying reversed rotary opposed forces to the ends of said spring means not fastened to said cam so that said turns release their grip on said shaft whereby the position of said cam relative to said shaft may be varied.

2. A control device for a radio receiver including a rotary tuning shaft, a cam mounted on said shaft for relative movement therewith, a pair of spirally wound springs coaxially arranged with respect to said shaft and positioned one on either side of said cam with the ends adjacent to said cam fastened thereto, means for applying opposed rotary forces to the ends of said springs not fastened to said cam to cause the convolutions of said springs to grip said shaft and fixedly hold said shaft and cam as a unit, a selector structure for causing rotation of said cam and tuning shaft as a unit when operated in a predetermined manner, and means on said selector structure when operated in a different predetermined manner for applying reversed rotary opposed forces to the ends of said springs not fastened to said cam so that said convolutions are unwound from said shaft to release their grip on said shaft whereby the position of said cam relative to said shaft may be varied.

3. A control device for a radio receiver including a rotary tuning shaft, a cam mounted on said shaft for relative movement therewith, a pair of spirally wound springs coaxially arranged with respect to said shaft and positioned one on either side of said cam with the ends adjacent to said cam fastened thereto, a pair of reversely rotatable housing members one housing each of said springs, means for fastening the end not adjacent the cam of each of said springs to its associated housing member, spring means for biasing said housing members for opposite rotation about said shaft to cause the turns of said springs to grip said shaft and fixedly hold said shaft and cam as a unit, a selector structure including a first lever and a second lever operable to cause rotation of said cam and tuning shaft as a unit, and means on one of said levers when actuated in a predetermined manner to neutralize the effect of said spring means whereby said springs release their grip on said shaft so the position of said cam relative to said shaft may be varied.

4. A control device for a radio receiver includ-

ing a rotary tuning shaft, a cam mounted on said shaft for relative movement therewith, a pair of spirally wound springs coaxially arranged with respect to said shaft and positioned one on either side of said cam with the ends adjacent to said cam fastened thereto, means for applying opposed rotary forces to the ends of said springs not fastened to said cam to cause the turns of said springs to grip said shaft and fixedly hold said shaft and cam as a unit, a selector structure comprising a finger actuated lever assembly for causing rotation of said cam and tuning shaft as a unit, and means on said lever assembly transmitting a force applied to said lever assembly so that reversed rotary opposed forces are applied to the ends of said springs not fastened to said cam causing said turns to release their grip on said shaft whereby the position of said cam relative to said shaft may be varied.

5. Tuning apparatus for a radio receiver including a frame, a rotary control shaft journaled in said frame, control means on said shaft including a cam, means for releasably holding said cam in a fixed position on said shaft comprising a pair of spirally wound springs enveloping said shaft, one positioned on each side of said cam and each having the end thereof adjacent said cam fastened to said cam, a first hub housing one of said springs and fastened to the end thereof not fastened to said cam, a second hub housing the other of said springs and fastened to the end thereof not fastened to said cam so that rotation in opposite directions of said hubs causes the convolutions of said springs tightly to grip said shaft while reverse rotation of said hubs causes said convolutions to unwind from said shaft, a first arm fastened to one of said hubs, a second arm fastened to the other of said hubs, a tension spring interconnecting said arms to bias said hubs in a direction to cause said convolutions to grip said shaft, manual means actuatable to engage said cam to cause rotation of said cam and said shaft as a unit, a pair of release prongs associated with said manual means so that upon further actuation of said manual means said release prongs cause reverse rotation of said hubs with the unwinding of said convolutions from said shaft whereby relative movement between said cam and said shaft can be obtained.

6. A control device for a radio receiver including a rotary shaft, a cam mounted on said shaft for relative movement therewith, means enveloping a substantial length of said shaft for holding said cam in a predetermined fixed position on said shaft, a selector structure for causing rotation of said cam and said shaft as a unit, means on said selector structure for causing said first mentioned means to release said cam so that relative movement between said control unit and said shaft can be obtained, and rotatable means for preventing inadvertent operation of said last mentioned means.

7. Tuning apparatus for a radio receiver including a frame, a rotary control shaft journaled in said frame, control means on said shaft including a cam, means for releasably holding said cam in a fixed position on said shaft comprising a spirally wound spring enveloping said shaft and having one end thereof fastened to said cam, means for biasing said spring so that the spiral turns of said spring tightly grip said shaft to hold said cam in said fixed position relative to said shaft, manually actuatable means for engaging said cam to cause rotation of said cam and said shaft, means associated with said manu-

ally actuatable means for releasing said means for biasing said spring so as to cause said spiral turns to release their gripping action on said shaft whereby relative movement between said cam and said shaft can be obtained, and means eccentrically pivoted on said frame for preventing inadvertent operation of said means associated with said manually actuatable means.

8. In a control device for controllable apparatus having a movable element therein and a control member adjustably mounted on said element, mechanism for operating said control member and releasably maintaining it in an adjusted position on said element including in combination a helical spring operatively connected with said control member and movable relative to said element to grip the same and to provide a member-holding force, and a selector unit having a pair of relatively pivoted portions with one portion operatively connectable with said spring to move the same to simultaneously release a holding force on said element and release said control member from said element, and having another portion operatively connectable with said member to hold the same against movement when the holding force is released and while said element is moved relative thereto.

9. In a control device for controllable apparatus having a movable element therein and a control member adjustably mounted on said element, mechanism for operating said control member and releasably maintaining it in an adjusted position on said element including in combination a helical spring on said element operatively connected with said control member and adapted selectively to grip said element or be released therefrom, and a pivoted selector unit having a pair of pivoted portions therein movable relatively to one another, with one of said portions being connectable with said member upon application of a pivotal pressure to said unit to move the same to a control position, and with the other portion upon further application of pressure to said unit being operatively connectable with said spring to move the spring in a manner to release the gripping pressure from said element.

10. In a control device for controllable apparatus having a movable element therein and a control member adjustably mounted on said element, mechanism for operating said control member and releasably holding it in an adjusted position on said element including in combination a pair of helical springs on said element with one on each side of said control member and operatively connected therewith to provide a holding force therefor, and a selector unit having one portion for moving said control member and another portion movable relative to said first portion and operatively connectable to said pair of springs to simultaneously move the same and release the holding force thereof.

11. In a control device for controllable apparatus having a movable element therein and a control member adjustably mounted on said element, mechanism for operating said control member and releasably holding it in an adjusted position on said element including in combination a pair of helical springs on said element movable in opposite directions thereon with one on each side of said control member and operatively connected therewith to provide a holding force therefor, structural means corresponding to each of said two springs and operatively connected therewith, and a selector unit having one

portion for moving said control member and another portion movable relative to said first portion and connectable with said pair of structural means to simultaneously move the same and the springs therewith in opposite directions and release the holding force thereof.

12. In a control device for controlling apparatus having a movable element therein and a control member mounted on said element, the combination for operating said control member and releasably maintaining it in an adjusted position on said element including a spirally wound spring on said element operatively connected with said control member for frictionally holding said control member in a fixed position on 15 said element, a selector unit for moving said member and said element as a unit including an actuating means, and means on said actuating means and movable relative thereto for causing said spring to release from said element and permit relative movement between said control member and said element.

13. A control device for a radio receiver hav-

ing a movable element and a control member thereon, the combination including a spirally wound spring associated with said element and operatively connected with said control member 5 for holding said control member in a fixed position on said element, and a selector unit having a portion for moving said member and said element as a unit, and having another portion movable relative to said first portion to operatively connect with said spring for causing said spring to release said element from said member so that relative movement between said control member and said element can be obtained.
